UNITED STATES PATENT OFFICE.

ALBERT J. SPRINGBORN, OF CLEVELAND, OHIO.

TELEPHONE REGISTRATION SYSTEM.

SPECIFICATION forming part of Letters Patent No. 740,053, dated September 29, 1903.

Application filed April 29, 1903. Serial No. 154,741. (No model.)

To all whom it may concern:

Be it known that I, ALBERT J. SPRINGBORN, a citizen of the United States, residing at Cleveland, in the county of Cuyahoga and 5 State of Ohio, have invented a new and useful Improvement in Telephone Registration Systems, of which the following is a specification.

This invention relates to telephone systems, and has more particular reference to the means employed for registering the calls made by parties to which some other party responds and also for registering the number of calls to which the wrong party responds, 10 so that the exact number of successful calls can be readily ascertained.

The invention also comprises certain locking-out features and other details of construction, as will hereinafter be fully described.

In the drawings, in which similar reference characters designate corresponding parts throughout the several views, Figure 1 is a diagrammatic view of the connections for two 25 telephones, said telephones having my invention applied thereto and being connected through the central station. Fig. 2 is a diagrammatic view, on a larger scale, of the various connections and parts at one of the telephones, the talking and signaling circuits being omitted. Fig. 3 is a perspective view of 30 one of the registers. Fig. 4 is a sectional view of one of the plugs for the connecting-cables at central, and Fig. 5 is a similar view 35 of a special plug.

The inequality in the charges actually made by telephone companies for their unlimited service—by which it costs a party making ten calls per day, for example, as much as it 40 costs another party who uses his telephone almost constantly—and the trouble and annoyance to users of party-line or limited-service telephones occasioned by being called upon by central to state their numbers whenever they make a call and in their having to rely entirely upon the honesty of the operator girl to check up and charge them with only the successful calls made give rise to considerable dissatisfaction among telephone-users. The telephone companies are 45 also deprived of considerable business, for the

reason that many people will not put up with the annoyances of a limited service and their needs not warranting the expense of an unlimited service they dispense with telephones 55 altogether. Furthermore, the companies lose extensively because of the failure of the operators to register the calls made by the subscribers to the limited service.

For the above reasons a good, simple, and 60 reliable system by which the calls from each telephone will be automatically registered at such telephone has been in demand, and it is for the purpose of satisfying this demand that I have invented the system shown in the 65 accompanying drawings, in which—

1 represents the hooks of the telephones A and B; 2 represents the receivers; 3, the transmitters, and 4 the call-bells. As these telephones have the usual talking and signaling circuits, it is not deemed necessary to 70 describe them further except to state that they are connected through the wires 5 and 6 with the main lines 7 and 8.

The central station is indicated at C, and 75 for purposes of simplicity of description and illustration is divided into a left and right switchboard *a* and *b*. This switchboard is of the multiple type, the jacks 9 and 10 being in multiple or parallel across the main lines 80 7 and 8. The jacks comprise the sleeves 11 and the springs 12.

13 and 14 represent the wires comprising 85 a cable at the central station, said wires being connected to the tube and tip conductors, respectively, of the plugs 15. One of these plugs is shown in section in Fig. 4, in which the said tube and tip conductors are indicated at 16 and 17, respectively. Projecting from the forward end of the tip is a pointed 90 spur 18 of insulating material, said material being secured to the tip in any suitable manner.

In Fig. 5 is shown a special plug 19 for a purpose hereinafter stated, said plug differing 95 from the plug 15 only in the respect that it has no tube 16. This plug also appears in Fig. 1, where it is shown as connected to the earth at *c* through the wire 20, battery 21, and wire 22.

The sleeves and springs of the jacks 10 are connected with the main wires 7 and 8 through

the wires 23 and 24. Of course these main wires may have as many jacks on the switch-board as may be necessary, there being as many jacks as there are sections in the multiple board.

At the rear of those jacks that are connected with the same set of main lines is a sectional wire 25, said wire being separable at points just to the rear of the jacks, although the sections are normally connected through the spring-terminals 26. When either of the plugs 15 or 19 is inserted in a jack, however, the pointed spur 18 on said plug separates the terminals and breaks the circuit through said wire. As shown at *d*, the wires 25 are connected to the earth.

As the connections for all the telephones are identical, I will describe the same for one telephone, it being understood that the description applies to all the telephones alike.

The telephone-hook 1 is pivoted at 27 and has an arm 28 extending rearwardly from said pivot, said arm being rigid with the hook. 29 is a conductor-plate that is mounted upon the arm, although it is insulated therefrom, as shown. 30 and 31 are segments that are adapted to be bridged by the plate 29 when the receiver is removed from its hook. The segment 30 is connected by the wire 32 to the wire 6, and the segment 31 is connected to a wire 33, that leads through a solenoid 34 to the negative side of a battery 35. This battery is connected, through the conductor 36, to the ground at *e*. 37 and 38 are other segments that are arranged below the segments 30 and 31 and in such a position that when the conductor-plate 29 moves from the latter segment it will bridge the lower segments. The segment 37 is connected with the wire 6 through the wire 39, and the segment 38 is connected to a wire 40, that leads to electromagnets 41 and 42 and thence to a wire 43. The electromagnets are connected through a soft-iron yoke 44, so as to have their free poles facing each other, the magnets being so wound as to give a north and a south pole. One end of the wire 43 terminates in one of a set of contact-pieces 44 and 45, the contact 45 being connected with the grounded wire 36 through the wire 46. The other end of the wire 43 terminates in a contact-piece 47.

The contact-pieces 44 and 45 are normally connected by a yielding contact-strip 48, that is carried by a lever 49, said lever being pivoted intermediate its length and being pulled in a direction to separate the contact-pieces by a spring 50. While the telephone-hook is down, the lever 49 is held with the strip 48 bridging the contacts by a pin 51 on the hook extension 28, and the lever is retained in this position by a hook 52, that engages with its upper end, said hook being normally pulled into engaging position by a spring 53.

54 is a lever that is pivoted intermediate its ends and that is held against the contact-point 47 by a spring 55. On the opposite

side of its pivot it bears against another contact-piece 56, said piece being connected, through the wires 57 and 58, solenoid 59, and wire 60, with the main wire 7. 61 and 62 are other contact-points, the former being connected, through wire 63, with the wire 33 and the other being connected directly to the wire 58. These contact-points are normally separated, but are adapted to be bridged at times by the lever 54.

The telephone-hook preferably terminates in a finger 64, that projects so as to be intercepted at times by the plunger 65 of the solenoid 34, said plunger being normally pushed into intercepting position by a spring 66, coiled thereabout. When the solenoid is energized, the plunger will be retracted to permit the hook to fly up or the finger 64 to descend, and when the said finger moves upwardly again the plunger is cammed back, so that the finger can pass it.

67 is a plunger for the solenoid 59, said plunger being connected with the hook 52, heretofore described. When the solenoid is energized, the plunger will be retracted to permit the hook to disengage the lever 49, so that the spring 50 can act to break the circuit at the contacts 44 and 45.

68 is a lever that is pivoted intermediate its length, with its lower end extending between the poles of the magnet 41 42, said lever being held with this end midway between the poles by springs 69 and 70. The lever is magnetized, so that the lower end *N* is either a north or a south pole. When the lower end is drawn to the left, Fig. 2, the upper end of the lever trips the lever 54, and thus breaks contact with the points 47 and 56 and connects the contacts 61 and 62.

71 and 72 are registers that are connected with the upper end of the lever 68 by means of slotted links 73 and 74 and the cranks 75 and 76. While any suitable form of register or indicating mechanism may be employed, I prefer to use the form shown in Fig. 3, in which the rocking movement of the crank 75 back and forth adds the number of such successive movements on the adding-wheels, said number appearing through a slot, as shown. When the upper end of the lever 68 is moved to the right, the register 71 will be operated, the pin-and-slot connection with the link 74 permitting such movement without operating the register 72. When, however, the lever is moved in the opposite direction, the register 72 will be operated, and the register 71 will remain stationary.

Having thus described the various parts and their connections, I will now describe the operation, assuming that party B desires to talk with party A. As B takes up his receiver the rear end of his hook swings downwardly, causing the plate 29 to bridge the segments 30 31, thus establishing a circuit from B's battery 35 through the following circuit: wire 36 to earth at *e*, through the earth

to *d* at the central station, wires 25, 8, 6, and 32, segments 30 31, wire 33, and solenoid 34 to the battery again. When the solenoid 34 is energized, the plunger is retracted, so that 5 the hook may continue its movement, which continues until the segments 37 38 are connected. As these segments are not connected with B's battery, there is no current therefrom at this time. The ascent of B's hook 10 closes his talking-circuit in the usual way and signals the operator at central, who plugs into B's jack to ascertain who is wanted. As she does this the spur 18 on the plug separates the contacts 26 and breaks the connection 15 with the earth at *d*. Having learned that B is wanting to talk with A, the operator plugs into A's jack and calls him in the usual manner. Responding to his call, A takes up his receiver and permits the contact-plate 29 to 20 bridge his segments 30 31, thus establishing a circuit from his battery 35 through the following connections: wire 36, earth from *e* to *e*, it being remembered that wires 25 are broken by the plugs at central, wire 36 in B's telephone, wire 46, contact-plate 48, wires 43 and 40, through the electromagnets 41 and 42, segments 37 38, wires 39, 6, and 8 to the central station, strand 14 of the cable, wires 24, 8, 6, and 32 to the segments 30 31, and wire 33 and solenoid 34 to A's battery again. In 30 passing through the electromagnets 41 42 the polarized lever 68 is drawn in one direction—say toward the magnet 41—which will result in adding one call to the register 71. It will 35 thus be seen that no call is registered unless A takes up his receiver to answer. The current from A's battery also draws back his plunger 65, so that his hook can continue its movement until it bridges the segments 37 40 38, when A's talking-circuit is established.

In order to prevent any possibility of interference from earth-currents through parts of the talking-circuit and also to prevent the interruption and false registration due 45 to other parties in party-line systems who could take down their receivers and cause registrations to take place on those telephones in the talking-circuit, I provide means for breaking the circuit leading to the ground at 50 each telephone as soon as registration at B's telephone has taken place.

When B's lever 68 was swung to operate his register, as above described, its upper end turned the lever 54 and closed the contacts 55 61 62, thus sending a current from B's battery 35 through the following circuit: wire 36, earth from *e* to *e* at A's telephone, wires 36 and 46, contact-plate 48, wire 43, lever 54, wire 57, solenoid 59, wires 60, 7, and 23 to the 60 jack and plug, strand 13 of the cable to the other plug and jack, wires 7 and 60, solenoid 59, wire 58, lever 54, and wire 63 to the battery again. As the current passes through the solenoids 59 the hooks 52 are lifted to release the levers 49, which swing so as to separate the contacts 44 45, and thus break the

connections with the ground at both telephones. To prevent the sudden breaking of the current when a hook 52 is lifted, the spring contact-strip 48 is provided, which will 70 continue the contact for a short time or until the hook at the other telephone has certainly been lifted.

The solenoids 34, with their locking-plungers, are employed to prevent the possible 75 cheating of the device by the party calling, who could depress his hook slightly to disconnect his segments 37 38 as soon as he had told the central operator whom he wanted and then wait with his hook in this position until the 80 other party had probably taken down his receiver. It being remembered that B's segments 37 38 must be bridged at the same time that A's segments 30 31 are connected, it will be seen that such an operation would 85 prevent registration. With the solenoids and plungers, however, it will be impossible for A to unlock his hook to talk until B's hook connects his segments 37 38.

When the wrong party answers to the call, 90 it is necessary to make some record of such fact, so that the exact number of successful calls can be ascertained. When such an answer is received, it is only necessary for B or the party calling to hang up his receiver, 95 which will cause the pin 51 on his hook to restore his circuit, and then call central and complain. The central operator then takes the special plug 19, which is connected with the ground at *e*, and inserts it into B's jack, 100 which closes a circuit through the following connections, starting from the battery 21, it being remembered that B's receiver is still off the hook: wire 20, tip 17, wires 8, 6, and 39, segments 37 38, wire 40, magnets 41 42, 105 wires 43, 46, and 36, ground *e* to *c*, and wire 22 to battery again. As this current passes through the magnets in a direction opposite to that for adding on the register 71, the polarized lever 68 will be swung in the opposite 110 direction, which will add the number of wrong answers on the register 72. By using a register that will subtract when moved backwardly it is evident that I can cause the same to show the number of successful 115 calls; but as the registers 72 indicate more or less accurately the mistakes made by the operators at central I prefer to use the two registers 71 and 72, as shown.

Having thus described my invention, what 120 I claim as new, and desire to secure by Letters Patent, is—

1. In a telephone system, a plurality of telephones having hooks for their receivers, an electric circuit that is controlled by the hooks 125 of any two of said telephones, and means for preventing the movement of the hook of one of the two telephones to talking position unless the hook of the other is fully raised.

2. In a telephone system, a plurality of telephones having hooks, an electric circuit that 130 is controlled by the hooks of any two of said

telephones, and a solenoid having a plunger for engaging the hook of one of the two telephones, said solenoid being in the said electric circuit, and said plunger engaging and 5 locking the said hook so that it cannot move to talking position unless the hook of the other one of the two telephones is fully raised.

3. In a system for indicating the number of 10 calls made from telephones, a plurality of telephones having receiver-hooks, indicating devices at each of the telephones, contact-pieces at the telephone that is calling, said pieces being electrically connected when the receiver-hook is fully raised, contact-pieces at 15 the telephone that is called, said latter pieces being electrically connected when the hook of that telephone is only partially raised, an electric circuit including all of said contact- 20 pieces, a source of electric power and an electromagnet in said circuit, and means whereby said electromagnet operates the indicating device at the telephone that is calling.

4. In a system for indicating the number of 25 calls made from telephones, a device at each of the telephones for indicating the number of answered calls made from the respective telephones, means whereby said devices are operated from the telephones that are called, 30 a second device at each of the telephones for indicating the number of wrongly-answered calls made from the respective telephones, an electromagnet, means for sending a current through said magnet in one direction to operate the first-mentioned indicating device, 35 and means for sending a current through the said magnet in the opposite direction for operating the other indicating device.

5. In a system for indicating the number of 40 calls made from telephones, the plurality of telephones, a device at each of the telephones for indicating the number of answered calls made from the respective telephones, means whereby the said devices are operated from 45 the telephones that are called, a second device at each of the telephones for indicating the number of wrongly-answered calls made from the respective telephones, an electromagnet having its north and south poles facing each other, a magnetized lever having one of its poles normally midway between the said magnet-poles, means for sending a current through the said magnet in one direction to move the lever in one direction to 50 operate one of the indicating devices, and means for sending a current through the magnet in the other direction to reverse the movement of the lever and thus operate the other indicating device.

6. In a system for indicating the number of 55 calls made from telephones, a device at each telephone for indicating the number of answered calls made therefrom, a source of electric power at the telephone that is called, a 60 grounded wire connected with said source of

power, a grounded wire at the telephone that is calling, connections for sending a current through said grounded wires to operate the said indicating device at the telephone that is calling, and means for breaking the circuit 70 leading to the ground at one of the telephones when the said indicating device is operated.

7. In a system for indicating the number of calls made from telephones, a plurality of telephones, a device at each telephone for indicating the number of answered calls made therefrom, a source of electric power at the telephone that is called, a grounded wire connected with said source of power, a grounded wire at the telephone that is calling, connections for sending a current through said grounded wires to operate the said indicating device at the telephone that is calling, and means for breaking the circuit leading to the ground at both of the telephones when the 85 said indicating device is operated.

8. In a system for indicating the number of calls made from telephones, a plurality of telephones, a register at each telephone for showing the number of answered calls made therefrom, an electromagnet, a lever moved by said magnet to cause the register to operate, a source of electric power at the telephone that is called, a grounded wire connected with said source of power, a grounded wire at the telephone that is calling, connections for sending a current through said grounded wires to move the said lever and thus operate the said register at the telephone that is calling, and a circuit-closer operated by the said register- 90 operating lever for closing a circuit and means in said circuit that causes the circuit leading to the ground to be broken, for the purpose 100 specified.

9. In a system for indicating the number of 105 calls made from telephones, a plurality of telephones, a device at the telephone that is calling for indicating the number of answered calls made therefrom, a grounded wire at said telephone, a grounded wire at the telephone 110 that is called, a source of electric power at the latter telephone for sending a current through the said grounded wires for operating the said indicating device, a source of power at the telephone that is calling, and a circuit-closer 115 for closing the circuit from the latter source of power when the said indicating device is operated and means in said circuit for breaking the circuit leading to the ground.

10. In a system for indicating the number of 120 unsuccessful calls from a telephone, a set of main lines, a telephone on said lines, a central station, a multiple switchboard at said central station, a jack in each section of the switchboard, said jacks being connected with the said main lines, a sectional wire extending past said jacks and connecting with the ground, a device at the telephone for indicating the number of unsuccessful calls made 125 therefrom, means operated at the telephone 130

for closing a circuit that includes the said sectional wire for signaling the central-sta-
tion operator, a second grounded wire at the central station, a source of electric power con-
nected with said wire, and a plug for the jacks on said wire, said plug having means for sep-
arating the sectional wire and for closing a circuit from the source of power that leads to

the said indicating device, for the purpose specified.

In testimony whereof I affix my signature in the presence of two witnesses.
